ATTORNEY

UNITED STATES PATENT OFFICE.

MARY McGEE, OF MUSCATINE, IOWA.

STOVEPIPE ATTACHMENT.

1,320,255.

Specification of Letters Patent. Patented Oct. 28, 1919.

Application filed November 4, 1918. Serial No. 261,020.

To all whom it may concern:

Be it known that I, MARY McGEE, a citizen of the United States, residing at Muscatine, in the county of Muscatine and State 5 of Iowa, have invented new and useful Improvements in Stovepipe Attachments, of which the following is a specification.

This invention relates to a stove pipe attachment which when applied will prevent 10 the stove pipe from being accidentally withdrawn from the stove pipe opening, or pushed therethrough a sufficient distance to interfere with the draft through the pipe. The primary object of the invention is to 15 provide an attachment for this purpose which comprises two members so constructed that they may be readily disengaged when the occasion requires and with one of the members serving as a holder 20 and a guide for a pin which not only prevents the stove pipe being pushed within the chimney but also prevents movement of the attachment upon the pipe.

With these and other objects in view, the 25 invention resides in the novel combination and arrangement of parts, which will be hereinafter described and particularly pointed out in the claim.

The preferred embodiment of the invention 30 has been illustrated in the accompanying drawings, although no restriction is necessarily made to the precise details of construction therein shown, as changes, alterations, and modifications within the scope of 35 the claim may be resorted to when desired.

In the drawings:

Figure 1 is a longitudinal section through 40 a portion of a stove pipe and showing the same retained in an opening in a chimney by the improved attachment which is also shown in section.

Fig. 2 is a view and elevation of the attachment removed from the pipe.

Fig. 3 is a view similar to Fig. 2 looking 45 at the reverse side of the attachment.

Fig. 4 is a view and elevation of one of the members comprising a part of the attachment.

Referring now to the drawing in detail 50 the letter A designates a portion of the chimney in the stove pipe opening 5 of which is retained the portion of a stove pipe 6 by the improved attachment 7.

The attachment 7 includes a ring 8 which 55 is mounted upon the pipe 6 and has secured to one side thereof the offset portions 9 of

retaining strips 10. The strips 10 pass through the opening 5 and extend within the chimney A, so that a portion of the strips may be bent, as at 10' to engage the inner wall of the chimney.

A collar 11 is mounted upon the pipe 6 and has formed therein at diametrically opposite points openings 12 which register with openings 13 in the pipe 6 adjacent the ring 8. A curved and circumferentially extending flange 14 is formed integrally with the collar 11 at one side thereof, and has formed therein openings 15 in line with the openings 12 in the band. Extending from the periphery of the flange 14 are tongues 16 and 17, the tongues 16 being arranged in pairs and like the tongues 17 are adapted to be bent over the ring 8 to lie between the ring and the outer face of the chimney A, thus detachably connecting the band 11 with the ring 8.

A headed pin 18 has a shank 19 which passes through the openings in the flange, the band and the pipe 6 do not only prevent movement of the ring and band circumferentially and longitudinally of the pipe 6, but also to prevent the pipe being pushed sufficiently forward through the stove pipe opening to interfere with the draft through the pipe.

When it is desired to employ the attachment for the purpose stated above the ring and band are connected by the tongues 16 and 17 and the strips are arranged within the opening 5 and adapted to engage the wall of the flue to maintain the ring 8 in place. The stove pipe 6 is now arranged within the opening 5 and the pin 18 arranged in place to lock the attachment upon the pipe.

From the foregoing description, taken in connection with the accompanying drawing, a stove pipe attachment has been provided which may be applied or removed from the stove pipe for the purpose set forth.

Having thus described the invention, what is claimed as new, is:

A stove pipe attachment comprising a ring disposed against a wall in encircling 105 relation to the flue opening therein, strips secured on said ring and extending within the flue opening and having their terminals bent for engagement within the flue to hold said ring against displacement, a 110 stove pipe extending through said ring and said flue opening, a collar disposed against

said ring and having its inner portion constituting a flange bearing against the stove pipe, the outer portion of said collar lying flat against the outer portion of said ring, 5 tongues formed integrally upon said collar and bent over the outer edge of and tightly engaging the rear face of said ring, and so-

curing means extending through said collar and said stove pipe for preventing movement of said pipe.

In testimony whereof I affix my signature.

MARY McGEE.
